UNITED STATES PATENT OFFICE

2,453,829

SHIPPING CARTON

Smith A. Blackman, Kirkwood, Mo., assignor to
 Gaylord Container Corporation, St. Louis, Mo.,
 a corporation of Maryland

Application September 26, 1946, Serial No. 699,577

1 Claim. (Cl. 229—23)

1 This invention relates to heavy duty shipping cartons of the kind shown in Beaman Patent No. 2,214,220 of September 10, 1940, wherein the tubular body and the end closures of the carton have side flaps that are held in interlocking engagement by an exterior encircling band.

The principal object of the present invention is to provide an end construction for such cartons that will increase the strength, rigidity, durability and load carrying capacity thereof; that will prevent leakage of powdered or granular material from the ends of the carton; and that will provide ice compartments at the ends of the carton. The invention consists in providing auxiliary top and/or bottom end closures that are clamped within the ends of the tubular body of the carton by the exterior locking band for the main end closures and have marginal flaps that seat against said main end closures and space the auxiliary end closures therefrom so as to form ice compartments in the ends of said tubular body. The invention also consists in the parts and combinations and arrangements of parts hereinafter described and claimed.

In the accompanying drawing, which forms part of this specification and wherein like symbols refer to like parts wherever they occur,

Fig. 1 is a side elevational view of a shipping carton embodying my invention,

Fig. 2 is a fragmentary plan view of the blank for the tubular body of the carton,

Fig. 3 is a plan view of a blank for one of the main end closures of the carton,

Fig. 4 is a plan view of a blank for one of the auxiliary end closures of the carton; and

Fig. 5 is an enlarged central vertical section through the carton on the line 5—5 in Fig. 1.

In the accompanying drawing, my invention is shown embodied in a heavy duty shipping carton of the type shown in Beaman Patent No. 2,214,220. Said carton comprises a tubular body A having interlocking end closures B, all preferably made of corrugated board, fiberboard or other bendable sheet material. The tubular body A is divided by vertical creases or scores 1 into side wall panels 2 and is made from a flat blank whose ends are overlapped and permanently secured together preferably by means of staples 3.

Each side panel 2 of the polygonal tubular body A has at each end thereof a projecting flap 4 adapted to be folded along a score or crease line 5 flatwise against the outside face of said panel. Each of the end closures B comprises a closure member of polygonal shape to fit over the ends 50 of the tubular body member A and has side

2 marginal flaps 6 corresponding in number to the body flaps 4 and score lines or creases 7 for facilitating bending of said flaps. The flaps 6 terminate at their outer ends in tuck or locking tongues 5 6^a that are marked off by score or crease lines 7^a. Each end closure B is placed opposite one end of the tubular body A, its flaps 6 are bent over the folded body panel flaps 4, and the locking tongues 6^a of the flaps of said end closure are 10 tucked beneath said folded body panel flaps so as to lie between the latter and the body panels 2. The flaps 6 of each end closure B have notches 8 in their adjacent side edges that constitute locking recesses for a retaining hoop or securing band 15 9 that tightly encircles said flaps and firmly clamps the locking tongues 6 between said flaps and the side panels 2 of the tubular body A, the ends of said hoop or band being permanently united by means of a suitable hoop lock or coupling member 10.

The tubular body A of the above carton is also provided with load sustaining auxiliary or inner end closures C, preferably of corrugated board, fiberboard or other bendable sheet material. 25 Each of these auxiliary end closures C is of polygonal shape and snugly fits within the end of the polygonal tubular body A at about the level of the retaining band 9 and has projecting side marginal flaps 11 corresponding in number to the body panels 2 and creases or score lines 12 for facilitating bending of said flaps. The flaps 11 of the auxiliary end closure C are bent toward the open end of the tubular body A so as to lie flatwise against the inner surfaces of the side wall 30 panels 2 of said body opposite the flaps 4 thereof. The flaps 11 of the auxiliary end closure C terminate flush with the end of the tubular body A and seat endwise against the main or outside end closures B therefor, and said auxiliary end closure is clamped tightly in said tubular body by the locking hoop 9. The flaps 11 of the auxiliary end closures C serve to space them inwardly of the main or outside end closures B, thereby forming auxiliary compartments 13 in the tubular body A 35 of the carton at the ends thereof.

By the arrangement described, the auxiliary end closures C serve to increase the strength, rigidity and durability of the carton and the load carrying capacity thereof. The auxiliary end closures C serve to resist the inward pressure of the locking bands 9 and thus enable the locking tongues 6^a of the main end closure flaps 6 to be rigidly clamped by the locking hoops 9 between the body panels 2 and the flaps 4. At the same time, the auxiliary end closures C are firmly

clamped in the ends of the tubular body A by the inward pressure of the locking hoops 8 thereon, thereby preventing leakage of the powdered or granulated material from the ends of the carton. If desired, the flaps 11 of the auxiliary end closures C may be adhesively or otherwise bonded to the inner faces of the panels 2 of the tubular body. The flaps 11 of the auxiliary end closures C serve to space the latter from the main end closures B and the spaces between said auxiliary and main end closures are adapted to form separate compartments in the ends of the carton for dry ice or for water ice in moisture proof bags, thereby adapting the carton for use in the shipment of perishable products. The auxiliary end closures C of the carton also take the vertical load of the contents thereof and thus prevent bulging of the main end closures B under such load and the concentrated wear on said main end closures due to said bulging.

What I claim is:

A shipping carton comprising a tubular body of uniform inside width from end to end having flaps at one end thereof bent to lie alongside the outer side face thereof, a main end closure seated against said end of said body and having marginal flaps that are bent to overlie said body flaps and are thence rebent to lie therebeneath and remov-

ably interlock therewith, a removable auxiliary end closure snugly fitting entirely within said end of said tubular body adjacent to said body and end closure flaps in spaced relation to said main end closure to provide a chamber between, said end closures, said auxiliary end closure having marginal flaps that lie against the inner side face of said tubular body and terminate substantially flush with said end thereof in endwise abutting relation to said main end closure, and a band tightly encircling said body and end closure flaps at substantially the level of said auxiliary end closure for locking said main and auxiliary and end closures to said tubular body member in a substantially immovable, reinforcing and dust-proof manner.
